GASIFIER

Carl B. Larsen, Racine, Wis., assignor to J. I.
Case Company, Racine, Wis., a corporation

Application October 21, 1936, Serial No. 106,775

14 Claims. (Cl. 123—133)

The present invention relates to internal combustion engines, and particularly to the carbureting apparatus thereof, and an object of the invention is to provide improved means for gasifying a liquid fuel and mixing it with air to form a suitable combustible mixture for an engine.

A further object is to provide for readily obtaining a suitable proportion of gas and air in the mixture under operating conditions.

10 A further object is to provide an improved structure for accomplishing the above objects and from which accumulations of carbon or the like may be readily cleaned, and other objects and advantages will become apparent from the following specification and accompanying drawings in which:

Figure 1 is a side elevation of a tractor embodying an engine including an example of the improved gasifying means.

20 Fig. 2 is a similar view of the gasifier alone, enlarged and with parts broken away.

Fig. 3 is a similar view depicting more particularly the flow of the various fluids in the device.

Fig. 4 is a vertical sectional view of the device 25 taken on line 4—4 of Fig. 2.

Fig. 5 is a vertical sectional view taken on the line 5—5 of Fig. 4, and showing certain parts in a different position.

Fig. 6 is a cross-sectional view of the retort 30 structure taken on the line 6—6 of Fig. 2.

Fig. 7 is a vertical sectional view of another portion of the retort taken on the line 7—7 of Fig. 2.

Fig. 8 is a similar view taken on the line 8—8 35 of Fig. 2.

Fig. 9 is a vertical sectional view on the line 9—9 of Fig. 2.

The invention is shown in Fig. 1 as applied to an engine used on a tractor including the usual 40 wheels 10 and 11, transmission housing 12, steering apparatus 13, fuel tank generally denoted by numeral 14, radiator 15, and engine 16, the gasifier of the present invention being carried by the engine, and generally designated by numeral 17. 45 In the present instance the engine 16 provides a plurality of inlet ports 18, Fig. 3, and exhaust ports 19, Fig. 4, which are closely related to the gasifier as will appear.

The gasifier proper, as readily seen in Fig. 3, 50 belongs to the general class in which an over-rich mixture is formed with a part of the entering air, the mixture being heated and diluted or blended with other air before being used in the engine. It comprises a plurality of passageways through which fuel and air are drawn by the

action of the engine, together with suitable liquid fuel feeding and controlling means. Thus the engine draws in mixture through the intake ports 18, this being supplied through an intake manifold 20 of usual or suitable form, and discharges 5 exhaust gases through exhaust ports 19, into an exhaust manifold generally designated as 21, which also serves a purpose in forming the combustible mixture.

The air is initially supplied through a pipe or 10 stack 22, Fig. 2, passing through a fitting 23, formed for convenience as part of the exhaust manifold, into an air cleaner 24 of suitable or well-known form, in the present instance having a removable reservoir or sump 25 for well-known 15 purposes.

Part of the cleaned air is induced through a passageway 26, Fig. 3, in a fitting 27, passing through a mixing or primary air passageway 28, in an atomizing portion generally denoted by 20 numeral 29, wherein it picks up liquid fuel, the resulting mixture passing through an exhaust heated retort 30 and a pipe or passageway 31 into a mixing throat or secondary air passageway generally denoted by numeral 32. The heating 25 effect of the relatively large retort 30 makes practical the use of fuels so heavy as to be ordinarily considered fit only for engines of the compression ignition type.

Other or secondary air, also from air cleaner 30 24, is induced through a passageway 33 in fitting 27, passing to mixing throat 32 through a passageway 34, where it meets the above mentioned mixture coming from pipe 31, the resulting finished or blended mixture passing out of the throat 35 into the intake manifold 20, and so into the engine.

The engine is started on gasoline or the like, and operated until the retort 30 is hot, after which it operates on heavy fuel, and the means 40 for supplying these fuels is as follows:

Tank 14, Fig. 1, is provided with two chambers 35 and 36, chamber 35 having an outlet valve 37 discharging into a fuel filter 38, and chamber 36 having a discharge valve 39, also discharging 45 into filter 38. From the filter a pipe line 40 leads to the liquid fuel supplying apparatus, so that, by means of the valves 37 and 39, it is possible to supply fuel to the engine from either of the chambers 35 or 36.

Atomizing portion 29, Fig. 3, in the present instance is a casting embodying the above described passageways 28 and 34, and, for supporting a float chamber or bowl 41, Fig. 2, it has a downwardly extending stem portion 42 passing 50 55

through the bottom of the bowl 41, which is clamped against a shoulder 43 on the stem by means of a nut or the like 44, the upper edge of the bowl seating against a suitable cover portion 45, on portion 29, and forming an upper closure 5 for the bowl. A suitable float 46 controls the level of liquid in the bowl in well known manner not shown.

Stem 42 is hollow and provides one or more openings 47 communicating from bowl 41 to the bore 48 of the stem. A fuel nozzle 49 is preferably fixed in an upper portion of stem 42, communicating with a bore 48 thereof, the discharge end of the nozzle being disposed in the present instance at about the mid-portion of mixing passageway 28, and within a Venturi tube 50, which, upon flow of air in passageway 28 will cause a reduction of pressure in nozzle 49, and atomizing of liquid therefrom, and accordingly from bowl 41. The liquid is broken up by the air blast into a spray and carried on to the engine after being gasified and diluted as above outlined. For regulating the proportions of fuel to air, a needle valve 51 is adjustable in a suitable bushing 52 and has a tapered portion 53 arranged to enter the nozzle a limited amount to control the flow of fuel therefrom, the amount of fuel allowed to flow depending upon the setting of the valve. In practice the mixture formed at this point is much too rich to fire, so that there is no difficulty from igniting of the fuel in the retort.

Retort 30 may or may not be formed as a single piece with exhaust manifold 21, but in the present illustrative embodiment it is shown as formed integrally therewith. It comprises a long passageway of relatively small cross section, and, in the present instance, flat, as shown particularly in Fig. 6, although other forms which would bring the mixture into intimate contact with the heated 40 walls are contemplated as equivalent.

The cross sectional area of the passageway is sufficiently small to insure the maintenance of a velocity of flow therethrough high enough to maintain the liquid spray in suspension until it is 45 gasified.

In the present instance the cylinders of the engine are divided into two groups, one group exhausting into a portion 54, of manifold 21, and the other group into a portion 55, and these portions are kept separate, one communicating with a passageway 56, Fig. 6, and the other with a passageway 57, these passageways being on opposite sides of passageway or retort 30. In this way the total quantity of hot gas is substantially equally divided, and the retort more evenly heated than it would be if the exhaust were allowed to discharge into a single chamber and then divided to pass on both sides of the retort.

Attention is particularly directed to the fact 60 that retort 30 is a straight passageway extending completely through an inclined portion 58 of manifold 21, the lower extremity or opening being covered during operation by a closure 59 maintained in position by a screw of the like as shown, 65 and the upper opening being covered by a similar closure 60, held by a screw or the like 61.

It is therefore possible, by simply removing closures 59 and 60 to run a tool completely through the retort, and thus to readily remove 70 any accumulation of carbon, dirt, or other foreign matter which might occur therein. This idea may be further carried out, mixing passageway 28, above mentioned, registering in a straight line with a passageway 62 extending through the 75 lower end of portion 58 of exhaust manifold 21,

the end of this passageway being closed by suitable means such for example as a removable plug 63. This passageway may accordingly also be cleaned by the insertion of a suitable tool.

The upper end of retort 30 widens out into a 5 chamber 64, Fig. 8, from which leads a port 65 communicating with above mentioned pipe or passageway 31. This pipe, in the present illustrative embodiment, is composed entirely of straight sections so that drills or other tools can be run 10 through every part for cleaning. Thus as seen particularly in Fig. 4, the pipe comprises a straight middle section 66 having a transverse portion 67 provided with a flange 68 or other suitable means for attachment to manifold 21. Portion 67 is straight, and at one end opens into port 65, while at its other end it intersects portion 66 and is closed by a removable plug 69 which may be removed for the insertion of a cleaning tool, 15 which may pass clear through into chamber 64. Portion 66 is closed at its ends by plugs 70 and 71, which may be removed for cleaning, and a tool may pass completely through the portion as will be apparent. Pipe 31 has another transverse portion 72 connecting with above mentioned 20 blending throat 32, a flange 73 or other suitable attaching means being provided as shown.

A removable plug 74 permits insertion of a cleaning tool into portion 72, which tool may pass 30 completely through into the throat.

The stream of exhaust gas coming down portion 58 of manifold 21 passes directly to an exhaust pipe or stack 75 as clearly shown in Fig. 3, while that coming through portion 57 passes in front of retort portion 30 as shown in Fig. 7 35 through a by-pass chamber 76 to stack 75.

Fig. 5 shows the details of blending throat 32. It comprises a tubular portion 77 having a restriction 78 therein, and providing a port 79 through which the heated rich mixture from retort 30 and pipe 31 enters. Air flows upwardly in tube 77, and, under full flow conditions, restriction 78 causes enough reduction of pressure at port 79 to assure a sufficient flow in the pipe 31 and mixing passage 28 above mentioned to 45 cause efficient atomizing at the fuel nozzle 49. Under low throttle conditions restriction 78 assists in thoroughly blending the rich mixture and secondary air, causing smoother running of the engine than that obtained without the restriction. 50

A throttle valve 80 of butterfly or other suitable type is interposed in tubular portion 77 beyond port 79, and may be controlled in any suitable manner for regulating the speed and power of the engine, a connection 81 for this purpose, Fig. 1, 55 from a suitable or well known type of governor (not shown) being provided in the present instance. Manual control may be exercised over the engine by means of a lever 81' which may influence either the governor or the throttle in 60 any suitable or well known manner forming no part of the present invention.

Connection 81, as shown in Fig. 4, engages a lever 82 fixed on a shaft 83 journaled in substantially gas-tight manner in the walls of tube 77, 65 and upon which valve 80 is mounted.

At low throttle openings, there would be insufficient flow of air through restriction 78, Fig. 5, to provide the necessary vacuum at port 79, and the supply of mixture from pipe 31 would be 70 deficient. To provide against this contingency a valve 84 is arranged in tube 77 on the upstream side of restriction 78, this valve being mounted on a shaft 85, and normally controlled dependently with valve 80 above mentioned. 75

Shaft 83, as shown in Fig. 2, has an arm 86 having pivotally secured thereto an apertured member 87 through which passes a rod 88, preferably adjustably engaged with a clevis or the like 89 pivotally secured to an arm 90 fixed on above mentioned shaft 85. Rod 88 carries a stop 91 in the present instance above member 87, and a slideable collar 92 is urged by a spring 93 against the under side of member 87, the spring bearing at its other end against a collar 94 adjustably or otherwise fixed on rod 88. By screwing rod 88 into or out of clevis 89, the angular relation between arms 86 and 90 and accordingly the relative opening of the two valves can be adjusted. A lock-nut 95 is preferably provided, or other suitable means may be used to maintain the adjustment.

Normally stop 91 is maintained against member 87 by spring 93, and rod 88, and accordingly valve 84 partakes of movements of valve 80 and arm 86. In the event, however, that it is desirable to close, or partially close valve 84, as shown in Fig. 5, without affecting valve 80, this can be done, rod 88 sliding through the aperture in member 87, and collar 92, and spring 93 yielding to permit this movement.

This might be necessary in starting the engine, and it is readily effected by means of a "choke rod" 96 operable from a convenient position, 30 in the present instance in front of the tractor, and connecting pivotally with an arm 97, Fig. 2, loose on shaft 85, and having an abutment 85^a arranged to engage a pin or the like 85^b fixed on arm 90, to urge the arm in a direction to close valve 84. The rod can be actuated to close or substantially close valve 84 when cranking the engine so as to obtain a very strong suction through port 79 and mixing passageway 28. It should be noted that, under these conditions, the 40 tractor governor will be holding the valve 80 in its fully opened position, but, on account of the extremely low engine speed there will be very little flow in the tube 77, and virtually no vacuum in the neighborhood of port 79. Closing valve 84 causes substantially all the air drawn in to pass through port 79, and accordingly through mixing passageway 28, so that a suitable spray issues from nozzle 49, and the engine starts readily.

50 When the device is applied to an engine which is not equipped with a governor the valve 80 will ordinarily not be opened wide for starting, but only sufficiently to give a moderate idling speed, but, in any event, the restriction caused by valve 84 when closed is made to substantially exceed that of valve 80 when in starting position, so that a satisfactory draft of air is obtained through primary air passageway 28, retort 30, pipe 31, and port 79.

60 Immediately upon firing of the engine, the suction past valve 80 is enormously increased, so that the additional restriction caused by the closing of valve 84 is no longer necessary. Choke rod 96 is accordingly released, whereupon the spring 93 restores valve 84 to its correct running relation with valve 80, and the rod 88 and its associated mechanism maintains this relation, as above outlined.

65 Rod 86 may be retracted by suitable or well known means such as spring 96^a to remove abutment 85^a from pin 85^b, and prevent interference with free movement of arm 90.

In practical operation chamber 36 of tank 14, Fig. 1, is filled with gasoline or similar volatile fuel, while chamber 35 is filled with furnace oil,

Diesel oil, or other non-volatile fuel, and the gasoline, through valve 39, is allowed to flow into bowl 41, whereupon the engine is started as above explained. As soon as the engine fires, choke rod 96 is released so that valve 84 opens to an extent corresponding approximately to the opening of valve 80, but the large flow of air through restriction 78 occurring when the engine starts causes a sufficient vacuum at the mouth of port 79 to induce a strong flow of air through mixing passageway 28 so as to induce suitable atomizing of fuel at nozzle 49.

As soon as the engine reaches full speed, unless the load is heavy, the governor closes, or nearly closes valve 80, which results in a greatly decreased flow through tube 77, and this would result in a greatly reduced flow through mixing passageway 28 if it were not for the fact that valve 84 is also closed, and, by virtue of the adjustment provided in rod 88, in the ratio necessary to maintain a substantially constant, or suitable quality of mixture at various openings of throttle valve 80.

Flow of the exhaust gas through passageways 56 and 57 quickly heats retort 30, and in a short time after the engine is started valve 39 may be closed and valve 37 opened, whereupon heavy fuel flows through filter 38 and pipe 40 into bowl 41. As the resulting heavy fuel mixture passes through the hot retort 30 it is sufficiently heated 30 to be vaporized, the product flowing in pipe 31 being in the nature of a rich mixture of a dry gas and air.

The proportions of this mixture are readily controlled by suitable adjustment of needle valve 51, and the degree of blending of this mixture with fresh air in throat 32 is easily controlled by adjusting the rod 88, the first adjustment corresponding in a sense to the low-speed adjustment, and the second to the high-speed adjustment of an ordinary carburetor.

In this device, as above stated, it is practical to vaporize or gasify oils for use in an ordinary type of internal combustion engine, which previously have been usable only in engines of the 45 compression ignition type.

If the use of these fuels is attended with the deposit of a certain amount of carbon or other material in the retort 30 or connecting passageways 62 or 31, it is a simple matter to remove 50 the closures provided, when suitable cleaning tools or the like can be run through all of the passageways likely to receive such deposits. This is the work of only a few minutes, and need be done ordinarily only once in from one to seven 55 days with heavy fuels. With gasoline, kerosene, and the lighter distillates cleaning is usually not required, or if at all only at very long intervals.

While the disclosed embodiment of the invention shows an up-draft arrangement of the 60 parts, it is to be understood that the principles herein set forth are equally adaptable to a down-draft arrangement, and that the invention is not to be taken as limited to the arrangement shown, or in fact in any way except as 65 defined in the claims.

The upwardly inclined arrangement of retort 30 is advantageous in facilitating a compact arrangement of the various passageways, in obtaining a counter-flow arrangement of the heating and cooling gases, and in assisting in preventing the carrying over of unvaporized particles of the heavy fuel, and this arrangement also makes conveniently possible the division of the issuing exhaust gas into two separate streams 75

as above explained, resulting in a very even heating of the retort, which in turn is at least partly responsible for the extreme effectiveness of the device.

5. The above being a complete description of an illustrative embodiment of the invention, what is claimed and desired to be secured by Letters Patent of the United States is:

1. In a gasifier for an internal combustion engine, a primary air passageway, a fuel nozzle arranged to communicate with said passageway, a passageway leading to said engine, and spaced flow controlling valves in the second-mentioned air passageway, said primary air passageway communicating with said second-mentioned passageway between said valves, a connection from one of said valves to the other including a stop for positively actuating the second-mentioned valve from movements of the first-mentioned valve in one direction, a yieldable element arranged to impositively urge said second-mentioned valve from movements of said first-mentioned valve in the opposite direction, means for moving said first-mentioned valve for controlling said engine, and means for moving said second-mentioned valve independently of said first-mentioned valve by virtue of yielding of said yieldable element, for temporarily changing the relation between said valves.

30. 2. In a gasifier an air passageway, a fuel nozzle arranged to communicate with said air passageway, and said passageway being extended to form a fuel vaporizing retort, a manifold for collecting heated fluid, means dividing said manifold into a plurality of exhaust chambers, and independent passageways individual to said chambers and extending along the sides of said retort for thorough and uniform heating thereof.

35. 3. In a gasifier a primary air passageway, a fuel nozzle arranged to communicate with said primary air passageway, a manifold for collecting heated fluid, means dividing said manifold into a plurality of independent chambers, and a mixture heating retort between said chambers, a secondary air passageway, and connections for flow of fuel mixture from said primary air passageway into said retort, and from said retort to said secondary air passageway, there being means beyond said secondary air passageway for regulating the flow of mixture to a point of use.

40. 4. In a gasifier for an internal combustion engine, a manifold, tubular passageways extending from different portions of the manifold for conveying fluid from the latter and forming therebetween a longitudinally arranged retort heated by the fluid, means communicating with the retort for producing and conveying volatile mixtures into the retort, an air passageway, and means connecting the retort to said passageway for conveying heated mixtures into the latter.

45. 5. In a gasifier for an internal combustion engine, a source of heated fluid, tubular passageways extending from different portions of said source for conveying heated fluid from the latter and forming therebetween a longitudinally arranged retort heated by the fluid means communicating with the retort for producing and conveying volatile mixtures into the retort, an air passageway, and means connecting the retort to said passageway for conveying heated mixtures into the latter to be conveyed thereby to a point of use.

60. 6. In a gasifier a manifold for collecting heated fluid, a plurality of conduits independently connected to and communicating with different por-

tions of the manifold, said conduits being spaced apart to form a retort therebetween heated by fluid flowing through the conduits to an outlet, a primary air passageway communicating with the retort, a fuel receptacle associated with the passageway, a fuel nozzle communicating with the passageway and cooperating with the receptacle for atomizing fuel to be conveyed into the retort, a secondary air passageway and means connecting the retort to the secondary air passageway for conveying volatile mixtures into the latter to be thence discharged to a point of use.

65. 7. In a gasifier the combination of a manifold for collecting heated fluid, a plurality of conduits independently connected to and communicating with different portions of the manifold for conveying heated fluid therefrom, a retort between said conduits, and means for atomizing fuel to be conveyed through the retort and heated by the fluid in the conduits.

8. In a gasifier including a manifold, the combination, with the latter, of a combined retort and heating conduits positioned at opposite sides thereof, independently connected to and communicating with different portions of the manifold for conveying heated gases from the manifold along the sides of the retort for heating volatile mixtures passing therethrough.

9. In a gasifier for an internal combustion engine a primary air passageway, a fuel nozzle arranged to communicate with said passageway, means for supplying liquid fuel to said nozzle, a secondary air passageway, said passageways being arranged to join in a single passageway leading to said engine, a throttle valve in said single passageway, a regulating valve in said secondary air passageway, the junction between said primary and secondary air passageways being between said restriction and said throttle valve, whereby the reduction in pressure caused by said restriction under fully open throttle conditions will cause a draft of air through said primary air passageway, and a connection for operating said regulating valve dependently with said throttle valve and arranged to cause said regulating valve to restrict said secondary air passageway sufficiently under low throttle conditions to maintain a suitable vacuum to induce a sufficient flow through said primary air passageway to draw a proper quantity of fuel from said nozzle.

10. In a gasifier for an internal combustion engine a primary air passageway, a fuel nozzle arranged to communicate with said passageway, means for supplying liquid fuel to said nozzle, a secondary air passageway, said passageways being arranged to join in a single passageway leading to said engine, a throttle valve in said single passageway, a regulating valve in said secondary air passageway, a connection between said throttle valve and said regulating valve for dependent operation of said valves, a restriction in said secondary air passageway said restriction being such as to cause a vacuum in said secondary air passageway under full throttle conditions, such as to cause a draft of air in said primary air passageway sufficient to draw a proper quantity of fuel from said nozzle, and said connection being adjustable to cause said regulating valve, under various low-throttle conditions, to restrict said secondary air passageway sufficiently to maintain a draft of air in said primary air passageway sufficiently strong to draw a proper quantity of fuel from said nozzle under each of said conditions.

11. In a gasifier for an internal combustion engine, a primary air passageway, a fuel nozzle arranged to communicate with said passageway, a secondary air passageway arranged to join said primary air passageway, and a blended mixture passageway leading from the juncture of the aforesaid passageways to said engine, spaced flow controlling valves, one of said valves in said blended mixture passageway and another of said valves in said secondary air passageway, whereby said primary air passageway joins the other passageways between said valves, a connection from one of said valves to the other including a stop for positively actuating the second-mentioned valve from movements of the first-mentioned valve in one direction, a yieldable element arranged to impositively urge said second-mentioned valve from movements of said first-mentioned valve in the opposite direction, means for moving said first-mentioned valve for controlling said engine, and means for moving said second-mentioned valve independently of said first-mentioned valve by virtue of yielding of said yieldable element, for temporarily changing the relationship between said valves.

12. An exhaust manifold for an engine, said manifold being divided into a plurality of independent chambers, and including a plurality of independent discharge conduits individual to said chambers, said conduits being spaced apart and providing a mixture heating retort therebetween.

13. An exhaust manifold for an engine, said manifold being divided into a plurality of independent chambers, and including a plurality of independent, downwardly directed discharge conduits individual to said chambers, said conduits being spaced apart and providing a mixture heating retort therebetween, and said conduits being arranged to intercommunicate at their lower ends to provide a common discharge outlet.

14. An exhaust manifold for an engine, said manifold being divided into a plurality of independent chambers, and including a plurality of independent discharge conduits individual to said chambers, said conduits being spaced apart and forming therebetween a straight flattened tube of uniform cross section constituting a heating retort.
